UNITED STATES PATENT OFFICE

136,453

DESIGN FOR A LIGHTING FIXTURE

Charles T. Masterson, East Cleveland, Ohio, assignor to General Electric Company, a corporation of New York

Application August 14, 1943, Serial No. 110,915

Term of patent 7 years

To all whom it may concern:

Be it known that I, Charles T. Masterson, a citizen of the United States and a resident of East Cleveland, in the county of Cuyahoga and State of Ohio, have invented a new, original, and ornamental Design for Lighting Fixtures, of which the following is a specification, reference being had to the accompanying drawing, forming a part thereof.

Fig. 1 is a perspective view of a lighting fixture, as seen from below, showing my new design;

Fig. 2 is a transverse section of the same along the line 2—2 of Fig. 1, illustrating the appearance of the interior thereof and the curved, translucent, longitudinally extending side panels;

Fig. 3 is an end view of the same; and

Fig. 4 is a bottom plan view of the same.

I claim:

The ornamental design for a lighting fixture, as shown.

CHARLES T. MASTERSON.
